(57) **CLAIM**

The ornamental design for a 3D 8-shaped cat bed, as shown and described.

DESCRIPTION

FIG. 1 is a front perspective view of a 3D 8-shaped cat bed, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the 3D 8-shaped cat bed in a disassembled state;

FIG. 10 is an enlarged detail view of area 10 in FIG. 1; and, FIG. 11 is an enlarged detail view of area 11 in FIG. 1.

The long-dash short-dash dot broken lines in FIGS. 1, 10 and 11 show the boundaries of the enlargements shown in FIGS. 10 and 11 and form no part of the claimed design. The remaining broken lines in the drawings illustrate the portions of the 3D 8-shaped cat bed, which form no part of the claimed design.
